FURNACE CONSTRUCTION

Richard C. Wright, Bay Village, Ohio, assignor to
Iron Fireman Manufacturing Company, Portland, Oreg.

Application November 24, 1944, Serial No. 564,909

9 Claims. (Cl. 110—165)

1

This invention relates generally to furnaces for burning solid fuel and particularly to a sloping furnace front.

The main object of this invention is to provide an improved form of furnace front and protecting grate therefor by means of which the ashes may be removed from the grates and permitted to cool without discharging quantities of steam fumes and dust into the boiler room and in which special provision is made for obtaining the maximum holding capacity for ashes and for protecting the front of the furnace against radiant heat just below the fire door opening.

I accomplish this and other objects in the manner set forth in the following specification as illustrated in the accompanying drawings, in which:

Fig. 1 is a longitudinal vertical section through a fuel injector and its associated parts.

Fig. 2 is a front elevation of Fig. 1.

Fig. 3 is an enlarged section through a portion of the furnace front showing the front protecting grate.

Fig. 4 is a front elevation of Fig. 3.

Fig. 5 is a horizontal section along the line 5—5 in Fig. 3.

Fig. 6 is a fragmentary view showing a modified form of ash dumping edge over which ashes are discharged into the ash pit.

Similar numerals refer to similar parts throughout the several views.

Referring in detail to the drawing there is shown a furnace front 10 whose lowermost portion 11 slopes outwardly to provide increased ash holding capacity which is further increased by the formation of a pit 12 whose sloping bottom 13 extends upwardly to the ash pit door 14. The position of the grates 15 is indicated and the section 16 of refractory material constitutes the dumping edge over which the ashes are raked into the pit 12. The section 16 is supported by means of the structural bars 17 and 18 and by the wall 19, preferably provided with the closures 20 which seal the openings 21 through which ridings can be drawn along the floor 22 into the pit 12.

Slightly below the level of the top surface 23 of the section 16 is an angle bar 24 which is welded to the front 10. The front protecting grates 25 have the rounded face 26 and the forwardly turned horizontal portion 27 whose tip 28 is downturned to hook behind the angle 24 while the rearward side 29 is tangent to the rounded portion 26 and terminates in a horizontal point 30 which engages the furnace front 10. A rib

2

31 stiffens the member 29 and acts as a stop against the angle 24.

In Fig. 6 it will be seen that instead of using the refractory element 16, there is provided a hook grate 32 whose front protecting hook 33 engages the channel 34 of a corresponding member 35, the details of which are set forth in my co-pending application, Serial Number 552,720, filed Sept. 5, 1944, now Patent 2,411,918, December 3, 1946. The function of the members 32 and 16 are identical, it being understood that the opening 36 between the members 16 or 32 and the member 25 is sufficiently large to permit the dumping of ashes into the pit 12.

It will be understood that the sloping front 11 is provided with an opening 37 at each ash removal point, around which opening is placed a door frame 38 upon which is hinged an ash door 39 provided with the hinges 40 and handle 41.

Owing to the extreme slope of the door 39, it is either held firmly closed or just as firmly opened by gravity.

The furnace illustrated is provided with a fuel injection nozzle 42 which occupies the opening 43 in the refractory front 44. The details thereof will not be described herein as they form no part of the present invention except that it will be understood that fuel is discharged therefrom onto the grates 15.

It will be understood that in some cases the pit 12 may be omitted and in other cases the degree of slope of the member 37 may be varied in either direction to increase or decrease the additional space acquired by such slope, and that in some cases it may be found desirable to make the wall 11 vertical, provided it is an extension from the front 10, in order to provide the necessary additional amount of ash space. Directly above the pit 12 is formed an upright or vertical opening 45 in the refractory front 44. The furnace front 10 has formed therein a fire tending opening 46 which is covered by a fire tending door 47 provided with a refractory guard 48.

I claim:

1. A furnace construction consisting of a refractory wall having a furnace front disposed in front of same, said front having fire and ash pit doors mounted therein, a horizontal grate on a level with the bottom of the fire door extending to the inner side of the refractory wall and spaced from the interior of the furnace front to afford a passageway for ashes into the space behind said ash pit door and a closure for the space between said horizontal grate and the floor beneath said grate, the space between said clo-

sure and the ash pit door constituting ash storage space.

2. In a furnace front, the combination of a metal front having a refractory lining and having a fire tending opening formed in said front, a set of grates disposed behind said front below the lower edge of said opening, said front having an upturned angle secured to its inner side below the top of said grates, a front protecting hook grate adapted to engage said angle and having its top side flush with the bottom of the fire tending door opening and having its lower portion forwardly turned to engage the furnace front and having ribs formed thereon adapted to engage the rearmost side of the supporting angle member.

3. In a furnace front, the combination of a vertical metal front, a refractory lining for said front, a fuel discharge nozzle projecting through said front and lining, a fire tending door opening extending through said refractory front, a grate extending substantially along the level of the bottom of the fire tending door opening, an ash pit formed below the fire tending door opening, said refractory lining having its fire tending opening extending to the ash pit and a shield for the front beneath the fire tending door opening.

4. In a furnace, a combination of a fuel supporting grate structure, a furnace wall in front of the front edge of said grate structure, said wall having an upright opening formed therein extending above and below the fuel supporting surface of said grate, said wall having a closure for the front of said opening, the lower portion of which wall extends outwardly beyond the vertical plane of the furnace front and means for separating the space under said grate structure from said upright opening.

5. A furnace front mounted on the floor having an outwardly sloping lower portion extending to the floor line, and having an ash pit formed behind said sloping portion below the floor line, grates disposed above the sloping portion and spaced therefrom and from the front thereby forming an opening through which ashes may fall into said ash pit.

6. A furnace front mounted on the floor in combination with a set of horizontal grates, the outer end of which is spaced from the furnace front and disposed above the bottom of the furnace front, the lowermost portion of the furnace front being inclined outwardly from a plane near the under side of said grates to the floor line, said outwardly inclined portion having an ash outlet door formed therein, the space between the outermost end of said grates and the furnace front constituting an opening through which ashes can fall into the space behind the ash door.

7. In a device of the class described, a combination of a refractory lined furnace front having its lower edge resting on the floor and having a fire tending opening in the lower portion thereof extending to the floor line of the furnace front and said furnace having a pit formed under said fire tending opening, a set of grates disposed behind said refractory front above the floor line of the front and overhanging the innermost edge of the pit, a wall supporting said grates having an opening therein for the removal of riddlings from the under side of said grates, said opening having a closure therefor, a metal furnace front outside

of the refractory furnace front having the portion thereof covering the fire tending opening provided with a fire tending door above the grate level and an ash removal door below the grate level, the portion of said metal furnace front containing the ash removal door sloping outwardly therefrom.

8. A grate structure for the support of solid fuel during the combustion thereof, in combination with a floor above which said grate structure is mounted, a wall supporting the outermost edge of said grate structure, said floor having a pit formed therein under the outer edge of said grate structure, a refractory furnace front having a fire tending door opening therein, the lower edge of said opening being in alignment with said grate structure, a metal front on the outside of said refractory furnace front having the lower portion thereof sloping outwardly, said outwardly sloping portion having an ash removal door mounted therein, the lower edge of which is near the floor line, the bottom of said pit inclining downwardly from the ash removal door to a line under the outer edge of said grate structure.

9. A grate structure for the support of solid fuel during the combustion thereof in combination with a floor above which said grate is mounted, a wall supporting the outermost end of said grate, said floor having a pit formed therein outside of said wall and under the outer edge of said grate, a refractory furnace front having a fire tending door opening therein above said pit, a metal front on the outside of said refractory front having a fire tending opening therein registering with the fire tending opening in said refractory front above the plane of said grate, the lower portion of said metal front beneath said fire tending door opening having an ash removal door mounted therein.
